Figure 1 is a perspective view showing a chair embodying my new design;

Figure 2 is a top plan view thereof;

Figure 3 is a front elevational view thereof;

Figure 4 is a side elevational view thereof;

Figures 5, 6, 7 and 8 are sectional views taken respectively along the lines 5—5, 6—6, 7—7 and 8—8 of Figure 2;

Figures 9 and 10 are sectional views taken respectively along lines 9—9 and 10—10 of Figure 3; and

Figures 11 and 12 are sectional views taken respectively along the lines 11—11 and 12—12 of Figure 4.

The dominant features of the design reside in the portions shown in full lines.

I claim:

The ornamental design for a chair, as shown and described.
